[57] CLAIM

The ornamental design for a muffler for a jackhammer, as shown and described.

DESCRIPTION

FIG. 1 is a front view of a muffler for a jackhammer, showing my new design;

FIG. 2 is a left side view thereof;

FIG. 2 is a left side view thereof;

FIG. 2 is also right side view thereof;

FIG. 3 is a back view thereof;

FIG. 4 is a top view thereof;

FIG. 5 is a bottom view thereof;

FIG. 6 is a top perspective view showing the top, side and front thereof;

FIG. 7 is a side perspective view showing a side and front thereof;

FIG. 8 is a top perspective view showing the top, side and front thereof;

FIG. 9 is a bottom perspective view showing the bottom and back thereof; and,

FIG. 10 is a side perspective view showing the top, side and back thereof.

Elements shown in dotted are environmental only, and form no part of the claimed design.

FIG. 1

FIG. 2

FIG. 3

FIG. 4

FIG. 5

FIG. 6

FIG. 7

FIG. 8

FIG. 10
